UNITED STATES PATENT OFFICE.

LOUIS A. JONES, OF WEST SOMERVILLE, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

MACHINE FOR CUTTING IN THE SHANKS OF SHOES.

1,161,052.

Specification of Letters Patent. Patented Nov. 23, 1915.

Application filed February 7, 1910. Serial No. 542,438.

To all whom it may concern:

Be it known that I, LOUIS A. JONES, a citizen of the United States, residing at West Somerville, in the county of Middlesex and State of Massachusetts, have invented new and useful Improvements in Machines for Cutting in the Shanks of Shoes, of which the following is a specification.

This invention relates to improvements in machines for performing the final trimming operation on the edges of a shoe sole in front of and up to the line of the heel breast, which operation is commonly known as "cutting in." Prior to the "cutting in" operation, the shoe is operated upon by a heel trimming machine which trims the outer edge of the heel and rands the upper edge of the heel adjacent to the outer edge thereof; the breasting of the heel then takes place. The shoe is next operated upon by an edge trimming machine which trims the outer edge of the forepart of the sole and rands the upper edge thereof. The shank portion of the sole edge is next operated upon by a rotary cutter which trims the outer edge and rands the upper edge of the shank portion. The shape of this cutter is such that it is necessary to terminate its operation some distance forward of the line of the heel breast. This leaves a certain amount of material adjacent to and in front of the heel breast which must be removed by the final trimming operation called "cutting in."

The object of this invention is to provide a simple, practical machine which shall be capable of neatly and expeditiously performing the "cutting in" operation.

The invention consists in the novel features of construction and in the combinations and arrangement of parts set forth in the following specification and particularly pointed out in the claims.

Referring to the drawings: Figure 1 is a side elevation of a "cutting in" machine embodying my invention. Fig. 2 is an enlarged detail view showing in cross section a shoe and a portion of the endless band operating upon said shoe together with the means for positioning said shoe with respect

to said band. Fig. 3 is a plan of the positioning means, the endless band being shown in section and a shoe being shown as the same appears when being operated upon on one side of the shank portion thereof. Fig. 4 is a view similar to Fig. 3, showing the machine operating upon the opposite edge of the shoe sole. Fig. 5 is a detail perspective view of the plate which constitutes a guide and support for the endless band and which is provided with breast gages, one of which is intended to engage the breast of the heel upon one side of the shoe and the other of which is intended to engage the breast of the heel upon the other side of the shoe. Fig. 6 is a detail elevation showing the working face of one form of endless band. Fig. 7 is a very much enlarged edge view of the band shown in Fig. 6. Fig. 8 is an elevation of a portion of the working face of another form of band. Fig. 9 is a very much enlarged edge view of the band shown in Fig. 8. Fig. 10 is a side elevation of another "cutting in" machine embodying my invention. Fig. 11 is an enlarged detail view showing in cross section a shoe being operated upon by the band, showing also the positioning means for positioning the shoe with respect to the band. Fig. 12 is a detail plan of the parts shown in Fig. 11, the band being shown in section and the shoe being omitted.

Like numerals refer to like parts throughout the several views of the drawings.

In the drawings, referring to Figs. 1 to 9, inclusive, 15 is an endless band which may be formed of any suitable material and which has suitable provision for cutting or abrading the edge of the shoe sole upon which it is to operate. In Figs. 6 and 7, I have shown the band as being provided with a surface formed of abrasive material which may be applied to the band, for example, by coating the band with an adhesive and applying the abrasive material to the adhesive while the adhesive is moist. In Figs. 8 and 9, I have illustrated a band which is formed of very thin flexible steel having its working face provided with teeth extending diagonally thereacross similar to files of a certain

class. A longitudinal movement is imparted to the band 15 by suitable means such as two pulleys 16 and 17 to which said band is connected, said pulleys being mounted to rotate upon a suitable frame 18 and the pulley 16 being driven by a driving pulley 19.

Secured to the frame 18 is a bracket 20 constituting a support for the means for positioning the shoe with respect to the band 15, such positioning means including two edge gages 21 and 22, two breast gages 23 and 24 and a crease gage 25. The edge gages 21 and 22 are adjustably mounted upon the bracket 20 so as to be capable of being adjusted transversely of the line of travel of the band 15, one of these gages being arranged to bear against the sole edge on one side of said band and the other being arranged to bear against the sole edge on the other side of said band. In practice, these gages will terminate in the plane of the working face of the band thus limiting the movement of the sole edge toward said working face.

The breast gages 23 and 24 may be and preferably are formed as flanges on a plate 26 secured to the end of the bracket 20 between the edge gages 21 and 22, said plate contacting with the band 15 opposite to its working surface and serving as a means for supporting said band against the pressure upon said working face when the shoe is placed thereagainst. The crease gage 25 constitutes also a means for guarding the shoe upper against the action of the band 15, said gage being preferably a very thin tempered steel plate secured in any suitable manner to a bracket 27 adjustably mounted on the bracket 20 and said gage being preferably somewhat resilient so as to be capable of yielding to a certain extent toward the working surface of the band 15 if sufficient pressure is applied thereto. This gage is adapted to enter the crease between the upper side of the sole and the upper of the shoe thus positioning the shoe sole longitudinally of the band 15 and with respect to the edge gages 21 and 22. The gage 25 may be and preferably is adjustably mounted on the bracket 27 so as to be capable of being adjusted longitudinally of the band 15 and with respect to the edge gages 21 and 22 so that said edge gages may be caused to bear against the edge of the shoe sole at any desired point in its thickness. The bracket 27 may be and preferably is adjustably mounted on the bracket 20 so as to make it possible to adjust the crease gage 25 transversely of the band 15 toward and away from the working face thereof.

The operation of the form of my invention hereinbefore specifically described is as follows: The shoe, after being operated upon by the heel trimming cutter and the shank trimming cutter, has a certain amount

of material forming a bunch upon the edge of the shoe sole at the shank portion thereof adjacent to and in front of the heel breast, as clearly shown in Figs. 3 and 4. The object of the machine of this invention is to remove this material and produce a beveled or rounded surface on the sole edge in front of and up to the line of the heel breast so as to form a continuation of the surface previously produced on the shank portion of the shoe sole by the shank trimming cutter. To perform this final trimming operation, the shoe is placed, as shown in Figs. 2 and 3, with the breast gage 24 against the breast of the heel and the crease gage 25 in the crease between the sole and the upper of the shoe so that the working face of the band 15 contacts with the edge of the shoe sole, as shown in said figures. Preferably, the band 15 travels in the direction of the arrow, Fig. 2, that is, from the lower toward the upper side of the shoe sole. It will be understood that the pulleys 16 and 17 may be made quite large in diameter so that a very high speed of the band 15 may be obtained without a very high speed of rotation of the shafts of said pulleys.

As pressure is applied to the shoe to carry the edge of the sole toward the working face of the band, said band acts to rapidly and smoothly remove the material sought to be removed and the proper cross sectional shape of the sole edge may be obtained by manipulating the shoe, it being evident that if the sole edge is required to be rounded the shoe may be rocked to a sufficient extent to produce the desired curvature, the edge gages 21 and 22 and the crease gage 25 being constructed and adapted to permit such movement.

Where one edge of the shoe sole is being operated upon, as shown in Fig. 3, the edge gage 21 finally encounters the edge of the sole at a point forward of the breast of the heel, and the edge gage 22 encounters the side of that portion of the sole edge which constitutes a part of the heel, it being evident that these gages prevent the band 15 from cutting into the sole edge beyond the proper depth and that the breast gage 24 is so constructed and arranged as to permit the band to cut up to the line of the heel breast without cutting into the heel breast.

The crease gage 25 serves to position the shoe longitudinally of the band 15, but does not prevent said shoe from being moved toward or from said band, the edge gages 21 and 22 being provided for limiting the movement of the shoe toward the band. The gage 25, as before stated, is interposed between the working face of the band and the upper of the shoe and, consequently, serves as a means for guarding the shoe upper against the action of the working face of the band and thus protects the shoe upper from

injury. After one side of the shoe sole has been "cut in" or trimmed, as hereinbefore described, the shoe is reversed and the breast of the heel placed against the breast gage 23, 5 as shown in Fig. 4, the operation upon this side of the sole edge being exactly the same as that upon the other side.

In some cases shoe soles have a very close edge, that is to say, there is but very little 10 extension beyond the side of the upper, and in operating on shoes of this class it is desirable to employ a means for deflecting the band from a straight path. In Figs. 10 to 15, inclusive, I have illustrated another embodiment of my invention particularly constructed for work of this class. In this embodiment of my invention, 28 is a band suitably formed to cut or abrade the edge of the shoe sole, as in the form of my invention 20 first described, this band having a longitudinal movement imparted thereto by pulleys 29 and 30 journaled on a suitable frame 31 and driven by a pulley 32. Secured to the frame 31 is a bracket 33 upon which are supported the means for positioning the shoe 25 with respect to the band 28 and the means for deflecting the band from a straight course so as to make it possible to operate on 30 shoes having a very close sole edge.

Adjustably mounted on the bracket 33 are two edge gages 34 and 35 corresponding to the gages 21 and 22, respectively, and also secured to said bracket are two breast gages 36 and 37, respectively, which perform the 35 same functions as the breast gages 23 and 24 of the form of my invention first described. Interposed between the edge gages 34 and 35 is a wheel 38 which may be journaled on any suitable support and in this instance is 40 journaled upon said gages, said wheel bearing against the band 28, thereby serving to deflect said band from a straight course and also serving as a means for supporting said band against pressure on the working surface 45 face thereof.

A crease gage 39 corresponding substantially to the crease gage 25 is adjustably mounted on a bracket 40 secured to the bracket 33, said crease gage constituting 50 also a means for guarding the upper of the shoe against the action of the band 28. This crease gage also is adjustable longitudinally of the band 28 and with respect to the edge gages 34 and 35 so that said edge gages 55 may be caused to bear against the sole edge at any desired point in the thickness of said sole. The gages 34 and 35 serve to determine the extent to which the sole edge can be moved toward the working face of the band 28 60 and in practice the extremities of said gages are located in the plane of said working face. These edge gages it will be noted, as well as the breast gages 36 and 37, project upon 65 the opposite sides of the band 28 and guide the same, thus preventing any tendency of

the band to swerve longitudinally of the sole edge.

The operation of this form of my invention is very similar to that of the form first described, it being evident that the shoe may 70 be placed with the breast of the heel against one of the breast gages and with the crease gage 39 in the crease between the sole and the upper of the shoe, said crease gage being adapted to yield toward the band 28 to allow 75 said band to cut into the sole edge and remove material therefrom until the edge gages 34 and 35 encounter the sole edge, thus preventing further movement, it being evident that in this case also the shoe may 80 be rocked to a sufficient extent to produce the proper cross sectional curvature upon the sole edge. In this case, the band being deflected away from the shoe upper permits as much of this rocking movement as may 85 be necessary to produce the desired cross sectional shape on the shank portion of the sole edge. In this case also, when the "cutting in" operation on one side of the sole is completed, the shoe is reversed and the 90 other side is operated upon in the same manner.

Having thus described my invention, what I claim and desire by Letters Patent so secure is:

1. In a machine of the class described, the combination of an endless band having an abrasive surface, means for imparting longitudinal movement to said band, and means for positioning a shoe with respect to said band so that the band shall operate upon the edge of the shank portion of the sole transversely of said edge, said positioning means including a gage arranged to extend between the edge of the band and the heel 100 breast of the shoe to protect the heel from contact with the band, said gage being so located with reference to the band as to permit the band to operate upon the sole edge substantially up to the line of the heel 105 breast, and means for engaging the shoe in the band crease to determine the position of the shoe in operative relation to the heel breast gage.

2. In a machine of the class described, the combination of an endless band having an abrasive surface, means for imparting longitudinal movement to said band, and means for positioning a shoe with respect to said band so that the band shall operate upon 115 the edge of the shank portion of the sole transversely of said edge, said positioning means comprising a gage arranged to contact with the breast of the heel of the shoe 120 to determine the position of the shoe transversely of the band, and means displaced longitudinally of the band from said breast gage constructed and arranged to engage 125 portions of the edge of the sole which have previously been trimmed, said means being 130

arranged with reference to the band to determine the depth of the cut of the band in the sole edge.

3. In a machine of the class described, the combination of an endless band having an abrasive surface, means for imparting longitudinal movement to said band, and means for positioning a shoe with respect to said band so that the band shall operate upon the edge of the shank portion of the sole transversely of said edge, said positioning means comprising a gage arranged to contact with the breast of the heel of the shoe to determine the position of the shoe transversely of the band, and a pair of gages positioned respectively at opposite sides of the band and arranged with reference to said heel breast gage to contact respectively with the edge of the sole at the rear of the heel breast line and in front of that portion of the edge which is operated upon by the band, said edge gages terminating substantially in the plane of the abrasive surface of the band so as to cause the band to trim that portion of the sole between the gages to substantially the same depth as those portions of the edge with which the gages are arranged to contact.

4. In a machine of the class described, the combination of an endless band having an abrasive surface, means for imparting longitudinal movement to said band, and means for positioning a shoe with respect to said band so that the band shall operate upon the edge of the sole transversely of said edge, said positioning means comprising a gage projecting forwardly at the front of the band and having an edge disposed transversely of the band for engagement in the rand crease of the shoe, and a pair of sole edge gages positioned respectively at opposite sides of the band beyond the end of the crease gage and arranged to limit the depth of cut of the band, said crease gage and edge gages being relatively arranged and constructed to permit the shoe to be rocked about the edge of the crease gage so as to cause the band to round the edge of the sole.

5. In a machine of the class described, the combination of an endless band, means for imparting longitudinal movement to said band, means for guiding the band in a path two portions of which are at an angle to each other, and means located adjacent to the apex of said angle for positioning a shoe with respect to said band so that the band shall operate upon the edge of the sole transversely of said edge, said positioning means comprising a gage in front of the band having an edge extending transversely of the band for engagement in the rand crease of the shoe, said gage being constructed to permit the shoe to be rocked about said edge while in engagement with the band.

6. In a machine of the class described, the combination of an endless band, means for imparting longitudinal movement to said band, means for guiding the band in a path two portions of which are at an angle to each other, and means located adjacent to the apex of said angle for positioning a shoe with respect to said band so that the band shall operate upon the edge of the shank portion of the sole transversely of said edge, said positioning means comprising a gage in front of the band having an edge extending transversely of the band for engagement in the rand crease of the shoe, the gage being constructed to permit the shoe to be rocked about said edge while in engagement with the band, and a gage arranged to contact with the heel breast of the shoe to position the shoe transversely of the band, said gage extending between the edge of the band and the heel breast to protect the heel from contact with the band as the shoe is rocked.

7. In a machine of the class described, the combination of an endless band adapted to cut down the edge of a shoe sole, driving means for said band, a heel breast gaging device positioned at each edge of said band and constructed and arranged to protect the heel breast from contact with said band while permitting the band to operate on the sole edge transversely thereof and substantially up to the line of the heel breast, said devices being operative alternatively on opposite sides of the shoe, and additional gages located at opposite edges of said band in position to engage the sole edge of the shoe to limit the operation thereon of said band.

8. In a machine of the class described, the combination of an endless band adapted to cut down the edge of a shoe sole, driving means for said band, a crease gage positioned in front of and close to said band, said gage having an edge extending transversely of the band in position to support the margin of a shoe sole for the operation of said band on the sole edge transversely thereof, two heel breast gages positioned respectively at opposite edges of said band and operative alternately on opposite sides of the shoe, and two sole edge gages located respectively at opposite edges of said band, all of said gages coöperating to position the shoe for the operation thereon of said band.

9. In a machine of the class described, the combination of an endless band having an abrasive surface, driving means for said band, a crease gage positioned in front of and close to said band, said gage having an edge extending transversely of the band in position to support the margin of a shoe sole for the operation of said band on the sole edge transversely thereof, a heel breast gage and a sole edge gage located at each side of

said band and coöperating with said crease gage to position the shoe for the operation of said band thereon, and a wheel positioned adjacent to said crease gage in rolling engagement with the face of said band opposite to said crease gage.

5 In testimony whereof I have hereunto set

my hand in presence of two subscribing witnesses.
